UNITED STATES PATENT OFFICE.

WILLIAM ESTY, OF LACONIA, NEW HAMPSHIRE.

DESIGN FOR A DISTRIBUTER FOR FIRE-EXTINGUISHERS.

SPECIFICATION forming part of Design No. 26,254, dated November 10, 1896.

Application filed October 12, 1896. Serial No. 608,663. Term of patent 14 years.

To all whom it may concern:

Be it known that I, WILLIAM ESTY, a citizen of the United States, residing at Laconia, in the county of Belknap and State of New Hampshire, have invented and produced a new and original Design for the Distributer of an Automatic Fire-Extinguisher, of which the following is a specification, reference being had therein to the accompanying drawings.

Figure 1 is a view in side elevation of a distributer showing my design. Fig. 2 is a view thereof in side elevation. Fig. 3 is a view thereof in vertical cross-section.

The leading feature of my design is the dentated crown-like shape which it presents in side elevation, the outer inclined face thereof flaring downwardly and outwardly. Another feature of the design is the concavo-

convex shape of the central portion or body 2, the outer edge of which rises and unites with the downwardly-flaring outer face 1 in the form of an angular ridge or wall 3, the upper edge of which is obliquely notched at 4 to give the dentated appearance above mentioned.

Having thus fully described my design, what I claim, and desire to secure by Letters Patent, is—

The design for a distributer for automatic fire-extinguishers, substantially as shown.

In testimony whereof I affix my signature in presence of two witnesses.

WILLIAM ESTY.
